CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a display screen or portion thereof with icon showing my new design; and,

FIG. 2 is a front view of a second embodiment of a display screen or portion thereof with icon showing my new design. The outermost broken lines in the figures show a display screen or portion thereof, and form no part of the claimed design. The other broken lines in the figures show portions of the icon that form no part of the claimed design.

1 Claim, 1 Drawing Sheet
